(57) **CLAIM**

The ornamental design for a plant holder, as shown and described.

DESCRIPTION

FIG. 1 is a top perspective view of a plant holder of the claimed invention.

FIG. 2 is a bottom perspective view of the plant holder of FIG. 1.

FIG. 3 is a front side elevation view of the plant holder of FIG. 1.

FIG. 4 is a back side elevation view of the plant holder of FIG. 1.

FIG. 5 is a left side elevation view of the plant holder of FIG. 1.

FIG. 6 is a right side elevation view of the plant holder of FIG. 1.

FIG. 7 is a top plan view of the plant holder of FIG. 1; and, FIG. 8 is a bottom plan view of the plant holder of FIG. 1. The broken lines in the drawings illustrate portions of the plant holder which form no part of the claimed design.
